UNITED STATES PATENT OFFICE.

THEODOR HLUBUCEK, OF CEDAR RAPIDS, IOWA.

TROUSERS-STEAMER.

1,243,176.

Specification of Letters Patent. Patented Oct. 16, 1917.

Application filed March 26, 1917. Serial No. 157,463.

To all whom it may concern:

Be it known that I, THEODOR HLUBUCEK, a citizen of the United States, residing at Cedar Rapids, in the county of Linn and 5 State of Iowa, have invented certain new and useful Improvements in Trouser-Steamer, of which the following is a specification.

This invention relates to certain new and 10 useful improvements in trousers steamers.

The primary object of the invention is the provision of a steaming form especially designed for steaming trousers although the same is applicable for steaming other garments, such as skirts, means being provided 15 for the ready control and heating of the steam employed with the device.

A further object of the invention is the provision of a garment steamer upon which 20 a pair of trousers is readily positioned and resiliently maintained thereon in stretched arrangement during the steaming operation whereby the leg portions thereof are suitably creased and a perfect shape given to 25 the garment.

A still further object is the provision of a steaming form having portions thereof expandible for reception within the leg portions of a pair of trousers, provision being 30 made for supplying steam therein suitably dried and heated.

In the drawing forming a part of this application and in which like designating characters refer to corresponding parts 35 throughout the several views:—

Figure 1 is a longitudinal sectional view taken upon line 1—1 of Fig. 2 with parts shown in elevation.

Fig. 2 is a top plan view of the device 40 with the steam drying pipe broken away.

Fig. 3 is a transverse sectional view through one leg member and taken substantially upon line II—II of Fig. 1, and,

Fig. 4 is a detail perspective view of the 45 shiftable section of one of the leg members of the device with a portion of the covering material cut away.

The present device being primarily designed for steaming trousers, the same 50 broadly consists of a hollow casing 10 of substantially the form of a pair of trousers and adapted for the reception of steam for passing through the trousers which are readily arranged thereon. An upright or 55 standard 11 has a base 12 and a mounting head 13, upon which head the end plate 14 of

the casing 10 is fixedly secured whereby the said casing is supported in a horizontal direction projecting perpendicularly from the standard 11. The casing 10 has its body- 60 portion 15 secured to the plate 14, bifurcations or leg portions 16 projecting from the body 15 in parallel relations with each other at the opposite end thereof from the plate 14.

Each of the legs 16 is expandible and in- 65 cludes a main lower portion 17, substantially V-shaped in cross-section, formed integral with the body 15, while an upper smaller section 18 also V-shaped in cross-section and inverted is vertically shiftable positioned 70 within the adjacent lower section 17.

The free outer ends of the sections 17 and 18 are closed by means of end walls 19 and 20 respectively, while perforations 21 are provided through both sections of the 75 legs 16 adapted for the passage of steam therethrough for heating as well as passing through a suitable covering 22 arranged thereon and adapted for engagement with the inner face of the trousers when opera- 80 tively positioned upon the casing 10.

A guiding means is provided for the leg sections consisting of opposite pins 23 carried by the lower sections 17 and arranged through vertical slots 24 in the upper sections 18, it being noted that looped springs 25 are arranged within the legs 16 bearing between the lower contracted end of the sections 17 and the upper pointed end of the section 18 tending to hold the said sections 90 in their extended positions. A fabric 26 is preferably arranged between the adjacent free inner edges of the upper section 18 and the lower section 17 for preventing the escape of steam between the said sections, al- 95 though the covering 22 of the upper section 18 serves as a packing between the said sections at their points of contact.

A steam filled pipe 27 has a T-shaped fitting 28 provided with branch pipes 29 100 which extend through the plate 14, the branch pipes being provided with perforated extensions 30 positioned within the legs 16, the branch pipes 29 being secured to the plate 14 by means of mounting bosses 36 105 with which the pipes 29 have screw-threaded engagement. A coil 31 surrounds the pipe 29 and has an inlet end 32 passing through the plate 14 and is provided with a T-fitting 33 externally of the casing that communicates with a similar coil associated with the other leg portion, while the opposite end 34 110

2
of each coil passes outwardly through the side of the body 15. It will be noted that the lower portion of the leg sections 17 are unperforated and are arranged inclined with respect to the lower portion of the body 15 for allowing the drainage of the condensed steam to flow outwardly of the casing 10 through a suitable drain pipe 35.

It will be understood that with the trousers arranged upon the casing 10 in stretched relation, steam is admitted by means of the pipe 27 and T-fitting 28 through the pipes 29 and 30 into the casing 10, suitable valve controlled means being provided therefor, the steam passing outwardly through the perforations 21 and the cover 22 and acting upon the trousers while the steam remaining within the device is maintained heated and is dried by means of the coil 31, the supply of steam thereto entering by means of the T-fitting 33. Springs 25 maintain the forward and rear portions of the trouser legs in close contact with the sharpened upper and lower edges of the casing legs 16, thereby imparting suitable creases thereto as well as pressing the trousers during the steam cleaning operation.

What I claim as new is:—

1. A garment steamer comprising a casing, expansible perforated members for the casing, spring means for expanding the same, steam supplying means therefor, and steam drying means therefor.

2. A garment steamer comprising a casing of trouser form having expansible leg portions arranged with perforations, spring means for expanding the same, perforated pipes arranged within the device, and a steam drying coil carried by the said pipes.

40 3. A device of the class described comprising a standard, a plate carried by the standard, a trouser form of casing having a body-portion secured to the plate extending horizontally and arranged with leg portions extending therefrom, each comprising upper and lower separate V-shaped sections, guide connections between the said leg sections, tensioned expansion means within the leg sections whereby the latter are normally maintained extended, and steam heating means within the casing.

4. A device of the class described comprising a standard, a plate carried by the standard, a trouser form of casing having a body-portion secured to the plate extend-

ing horizontally and arranged with leg portions extending therefrom, each comprising upper and lower separate V-shaped sections, guide connections between the said leg sections, tensioned expansion means within the leg sections whereby the latter are normally maintained extended, a steam pipe arranged through the said plate, a steam drying coil surrounding the steam pipe, and perforated branch pipes communicating with the supply pipe terminating in the said leg portions of the casing.

5. A device of the class described comprising a standard, a plate carried by the standard, a trouser form of casing having a body-portion secured to the plate extending horizontally and arranged with leg portions extending therefrom, each comprising upper and lower separate V-shaped sections, guide connections between the said leg sections, tensioned expansion means within the leg sections whereby the latter are normally maintained extended, a steam pipe arranged through the said plate, perforated branch pipes communicating with the supply pipe terminating in the said leg portions of the casing, a drain pipe arranged at the bottom of the said body-portion adjacent the said plate, the bottom of the lower leg sections being arranged inclined toward the said plate, and a steam heating coil arranged within the body-portion of the casing.

6. A garment steamer comprising a trouser-shaper casing having spring pressed expansible leg portions closed at the free ends thereof and provided with side perforations with inclined trough-shaped bottoms, a drain pipe carried by the casing adjacent the lower ends of said bottoms, and steam supplying means within the casing.

7. A garment steamer comprising a trouser-shaped casing having expansible leg portions closed at the free ends thereof and provided with side perforations with inclined trough-shaped bottoms, a drain pipe carried by the casing adjacent the lower ends of said bottoms, steam supplying means within the casing, a steam drying coil within the casing, and flexible means connecting the sections of said leg portions together adapted for the prevention of the escape of steam therebetween.

In testimony whereof I affix my signature.

THEODOR HLUBUCEK.
